UNITED STATES PATENT OFFICE.

EDGAR E. BROSIUS, OF PITTSBURGH, PENNSYLVANIA.

HOISTING-BUCKET.

1,228,526.

Specification of Letters Patent. Patented June 5, 1917.

Application filed April 5, 1916. Serial No. 89,051.

To all whom it may concern:

Be it known that I, EDGAR E. BROSIUS, a citizen of the United States, residing at Pittsburgh, Allegheny county, Pennsylvania, have invented a new and useful Improvement in Hoisting-Buckets, of which the following is a full, clear, and exact description, reference being had to the accompanying drawings, forming part of this specification, in which—

Figure 1 is an end view of a hoisting bucket embodying my invention, with the bucket sections in their open positions.

Fig. 1^a is a detail view showing a modification of a portion of the bucket structure.

Fig. 2 is a similar view showing the bucket sections closed, and

Fig. 3 is a side view with the bucket sections closed.

20 My invention has relation to hoisting buckets of the clam shell type; and is more particularly an improvement upon the bucket described and claimed in my Patent No. 1,087,105, dated February 17, 1914.

25 The bucket of the present invention retains all of the advantages of the bucket described and claimed in said patent, and is designed to possess certain further advantages, viz.; increased closing leverage on the bucket sections; a simple and efficient arrangement whereby the suspension rope or cable is also made to operate as an equalizing device for preventing too violent opening of the bucket and for taking up shocks; and an improved stop and guard arrangement for limiting the opening movement of the bucket sections.

30 The general construction of the bucket is in most respects similar to that shown and described in my said patent, to which reference is made for a more complete description. Similar parts in the present drawings are given the same reference numerals as in the said patent. In the present construction I have shown the central transverse lifting rod or shaft 6 as extending continuously across the bucket, the arms 4 of the bucket section 2 having their heads 5 rigidly secured to the shaft 6, as indicated at 4^a, while 35 the arms of bucket section 3 have pivot portions 5^a at their upper ends loosely bearing on said shaft.

35 The lever member 21 is fulcrumed on the central portion of the rod or shaft 6 between the collar portions 6^b of a guard and stop member 6^c secured to said shaft. This mem-

ber 6^c not only prevents endwise movement of the lever member 21 on the shaft 6, but it also forms a stop for the lever member 21 (as shown in Fig. 1), when the bucket sections reach their full open positions and the cross-head is lowered to the position shown in dotted lines in said figure. It further acts as a guard to prevent the dirt or other material upon which the bucket is lowered from being forced up into the working parts on the central portion of the rod or shaft 6. This member 6^c also has a projecting arm 6^d to which is attached one end of a flexible stop chain 6^e, the other end being connected at 6^f to the bucket section 3. Inasmuch as the arm 6^d is rigidly connected to the rod or shaft 6, which turns as the bucket section 2 opens, it will be readily seen that the opening movement will take up the slack of this chain 6^e, as shown in Fig. 1, the chain being taut when full open position is reached.

40 The dead end portions of the suspending rope or cable 14, instead of being fastened to the members 7^a as in my said patent, after passing around the sheaves 13, are carried up and around sheaves 40 which are journaled to the portions 7^a. Said dead end portions are then carried downwardly and 45 are connected to shackles 41 which are connected to members 42. These members 42 are shown as consisting of braces connecting the transverse rod or shaft 9 at the upper outer corner of the bucket section 3 with the 50 lifting rod or shaft 6. This connection of these members to the lifting rod 6 is not, however, essential, since said members may be in the nature of crank arms extending from the rod or shaft 9 as shown at 42^a in Fig. 1^a. In this form, the members 42^a are secured to the bucket section, and are rigidly engaged with the rod 9^a.

45 In the opening movement of the bucket it will be readily seen that the points 43 where the shackles 41 are connected to the member 42 will describe an arc about the centers 9, thereby exerting an increasing closing pull on the sections 2 and 3 as the latter open. This leverage action rapidly increases 55 toward the close of the opening movement, and is sufficient to prevent any shocks which would otherwise occur. The connections described act in a similar manner to the chains 18 of my said patent; but the present arrangement obviates the necessity for these chains and enables the same result to be ob-

tained by the rope or cable 14. Furthermore, the carrying of the dead end portions of this rope or cable upwardly over the sheaves 40, which are almost directly above the lifting rod 6, and thence downwardly to the points of attachment at 43, gives a very greatly increased closing leverage on the bucket sections.

The points of connection of the shackles 10 41 with the members 42 may be changed so as to give the desired amount of leverage. The leverage will rapidly increase as these points of connection are moved toward the lifting rod 6.

15 The general operation of the bucket is as described in my said patent.

I claim:

1. A hoisting bucket comprising a central lifting member, bucket sections swung about 20 the axis of said member, a cross head movable to position above and adjacent to the lifting member, coöperating latch means carried by the crosshead and by the lifting member, a toggle device connected to the 25 crosshead and to the lifting member, and a stop member for said toggle device also carried by the lifting member, together with a stop chain connected to said lifting member and with one of the bucket sections, substantially as described.

2. A hoisting bucket comprising a central lifting member, bucket sections swung about the axis of said member, one of said sections being secured to said member, a crosshead 35 movable to a position above and adjacent to the lifting member, coöperating latch means carried by the crosshead and by the lifting member, and a stop chain connected to the lifting member and to one of the bucket sections, substantially as described.

3. A hoisting bucket, comprising a central lifting member, two bucket sections swung at their upper inner corner portions about the axis of said member, link members pivotally 45 connected at their lower ends with the upper outer corners of said sections and with each other at their upper ends, a cross-head over the lifting member and movable vertically toward and away from the same, latch means 50 for connecting the cross-head to the lifting member, and a flexible suspension member connected at its end to one of the bucket sections at a point to cause an increasing pull 55 directly upon said suspension member throughout at least the major portion of the

opening movement of the bucket sections, substantially as described.

4. A hoisting bucket comprising a central lifting member, bucket sections carried thereby, a jointed frame to which the bucket sections are pivoted, a crosshead, latch means for engaging the crosshead with the lifting member, sheaves carried by the crosshead, other sheaves carried by said frame above the crosshead, and a flexible suspension member having its dead end portions carried around the sheaves on the crosshead and thence upwardly over the sheaves carried on said frame, and thence downwardly and connected at their ends to one of the bucket sections at points which cause an increasing pull directly on said suspension member during the opening movements of the bucket sections, substantially as described.

75 5. A hoisting bucket comprising a central lifting member, bucket sections carried thereby, a jointed frame to which the bucket sections are pivoted, a crosshead, latch means for engaging the crosshead with the lifting member, sheaves carried by the crosshead, other sheaves carried by said frame above the crosshead, and a flexible suspension member having its dead end portions carried around the sheaves on the crosshead and thence upwardly over the sheaves carried on said frame, and thence downwardly and connected at their ends to one of the bucket sections, said section having inwardly projecting members at its upper corner portions to which said ends are connected, substantially as described.

6. A hoisting bucket comprising a central lifting member, bucket sections carried thereby, a jointed frame to which the bucket sections are pivoted, a crosshead, means for engaging the crosshead with the lifting member, and a suspension member engaging the crosshead and having its end portions connected with one of the bucket sections so that the rope itself acts as a shock absorber for the bucket sections, substantially as described.

In testimony whereof, I have hereunto set my hand.

EDGAR E. BROSIUS.
